Application August 30, 1950, Serial No. 182,367

6 Claims. (Cl. 315—3)

1

This invention relates to improvements in systems for generating high frequency electromagnetic wave energy, and particularly to oscillators utilizing the principle of the travelling wave amplifier, wherein a stream of electrons is made to exchange energy with a wave propagating at substantially the electron velocity, throughout an extended interaction space. Prior art oscillators for operation at centimeter wavelengths have had the disadvantage of being tunable only through a relatively narrow frequency range; for example a reflex klystron of the deformable cavity resonator type may be tuned over a band of about plus or minus 15 percent. Accordingly, one of the principal objects of the present invention is to provide high frequency oscillators which are tunable throughout relatively wide frequency bands.

While it is known that travelling wave tubes may be made to oscillate without the provision of any external feedback means, and in fact will oscillate spontaneously unless something is done to prevent oscillations, it has not been possible heretofore to control the frequency of oscillation to a practical extent. The tube will tend to oscillate at one or more of a number of discrete frequencies, but not at other frequencies. The specific frequencies at which oscillation can occur will depend upon the electrical length of the wave propagating structure, and are characteristic of a particular tube. Previous attempts to vary the effective length by means of movable shorting or reflector devices have not been successful owing to the fact that waves travelling in a longitudinal electric mode, as on a slow wave propagating structure such as a helix in a travelling wave tube, will be largely converted into higher order mode waves which are dissipated instead of feeding back to sustain oscillation at a desired frequency. Thus it is another object of the invention to provide travelling wave tube oscillators which include adjustable means for reflectively terminating the wave propagating structure without substantial conversion of the longitudinal waves into spurious modes.

The invention will be described with reference to the accompanying drawing, wherein the single figure is a longitudinal cross section of a presently preferred embodiment thereof.

The travelling wave tube in the illustrated system comprises an electron gun 1, a slow wave propagating helix 3, and an electron collector electrode 5 enclosed in an evacuated envelope 7 of dielectric material such as quartz. The electron gun 1 includes a cathode 9, focussing electrodes 11 and 13, and an accelerator electrode 15.

2

arranged in known manner to produce and direct a beam of electrons travelling within and along the axis of the helix 3 to the collector 5. The cathode 9 includes a heater adapted to be energized from an external source such as a battery 17.

A direct current source such as a battery 19 may be connected to maintain the focussing, accelerating and collecting electrodes at the required potentials with respect to each other and the cathode. Typical voltages for the various electrodes are:

Cathode	Zero or ground
Focussing ring 11	—45
Focussing ring 13	+3000
Accelerator 15	0 to 2000
Collector 5	0 to 6000

The voltages at the accelerator and collector electrodes may be varied, as by means of adjustable voltage dividers 21 and 23 respectively connected across appropriate sections of the source 19. The D.-C. potential of the helix 3 may be maintained the same as that of the collector 5 by connection thereto through a wire 25.

The helix 3 is a conductive winding of uniform pitch, terminating at its ends in transition sections 27 and 29 respectively. These transitions may be identical, each consisting of a hollow tubular conductor 31 provided with a helical slot 33. The pitch of the slot 33 varies from a value substantially equal to that of the helix, at the point where the helix is connected to the transition section, to a value of infinity (i.e. the slot becomes parallel to the axis of the tubular member) toward the end remote from the helix.

A tubular outer conductor 32 surrounds the travelling wave tube throughout substantially its entire length, extending well beyond the ends of the transition sections 27 and 29, and is of relatively large diameter so as to be radially spaced from the helix far enough to have no effect on any radio frequency fields associated with the waves travelling on the helix 3. The middle portion of the conductor 32, around the helix 3, functions only as protective cover and mechanical support, and may be omitted if desired.

A short circuiting plug 35 is provided near one end of the tube, extending radially between the outer conductor 32 and the end of the transition section 27. The plug 35 as shown is of the non-contacting type, being designed to resonate with the capacitance between its inner wall and the conductive member 31 to provide an effective low impedance radio frequency connection between

the conductors 32 and 31 without requiring an actual metallic connection through the wall of the quartz envelope 7. The outer wall of the plug 35 may be in contact with the outer conductor 32. An output coupling loop 34 is provided near the plug 35, and is connected to and may be supported by a coaxial line 36 extending to any suitable load or utilization device, not shown.

A longitudinally movable short circuiting plug or tuning plunger 37 is provided at the other end of the tube, beyond the transition section 29. The tubular conductor 31 at this end is extended as shown at 39 to allow for substantial longitudinal travel of the plunger 37 through a region beyond the point where the pitch of the slot 33 becomes infinite. The plunger 37 is preferably of the non-contacting or choke type, both at the conductor 31 and the outer conductor 32, and is supported on a piston member 41 slidable longitudinally within the conductor 32. To provide for convenient adjustment of the plunger 37, the piston 41 may be coupled through a leadscrew 43 and gears 45 or equivalent means to a crank 47.

Any electrical disturbance will initiate a plurality of waves of different frequencies, each of which will propagate along the helix to one of the transition sections 27 or 29. The mode of propagation is one in which the electric field vectors extend longitudinally of the helix, being curved but lying substantially within planes which include the axis of the helix. This mode is referred to hereinafter simply as a longitudinal, or longitudinal electric mode.

As each wave reaches one of the transition sections, it is confronted with the variable pitch slot 33 and its electric field vectors are twisted toward a plane perpendicular to the axis. The longitudinal mode is gradually transformed into a radial or TEM mode, with the electric vectors extending radially between the tubular conductor 31 and the outer conductor 32 as in the principal mode of an ordinary coaxial transmission line. Owing to the continuous nature of the transformation, substantially all of the longitudinal mode field is transformed into the radial mode, without generation of any spurious or undesired modes.

The wave travelling in the substantially pure TEM mode is effectively reflected by the shorting device, and travels back along the transition section, which reconverts it to the longitudinal mode for propagation along the helix to the other end of the structure. Thus the transition sections 27 and 29, together with the shorting devices 35 and 37 and the adjacent portions of the outer conductor 32, cooperate to act as reflectors at each end of the helix 3. When the wavelength is such that the electrical distance between these reflectors is an integral number of half wavelengths, the waves travelling in opposite directions are phased so as to set up a standing wave, i. e. the helix 3 and the reflectors act as a resonator.

The wave component travelling in the same direction as the electron beam will interact therewith, providing that the electrons are travelling at about the same velocity as the wave, and cause the stream to form into bunches. As the bunches travel with the wave, some of the kinetic energy of the electrons is converted into wave energy, causing the wave to increase in amplitude as it travels along the helix from left to right as shown in the drawing. The amplified wave is reflected at the plunger 37 and returned

substantially without attenuation to the plug 35, where it is again reflected to travel in energy exchanging relationship with the electron stream.

Thus oscillations will build up to a point where the power given up by the wave, by losses in the tube and by extraction through the output coupling loop 34, is equal to the power delivered to the wave by the electron stream.

The helix 3, like most slow wave propagating devices, is more or less dispersive, i. e. the velocity of wave propagation depends upon the frequency of the wave being propagated. For the purpose of the present invention, it is preferable that the helix be designed to be as dispersive as is possible consistent with other factors such as reasonable gain per unit length. To produce oscillation at a selected frequency, the voltage dividers 21 and 23 are adjusted to make the velocity of the electrons conform approximately to the propagation velocity in the helix of waves of the desired frequency. The position of the plunger 37 is then adjusted by means of the crank 47 to make its electrical distance from the plug 35 exactly an integral number of half wavelengths at said frequency.

It will be apparent that there may be a number of possible positions for a given frequency, for example those corresponding to 19, 20, and 21 half wavelengths; any such position is suitable. Coarse adjustment to any frequency within a very wide band may be effected by variation of the accelerating voltage by the voltage divider 21, and fine adjustment to an exact frequency within the relatively narrow band corresponding to a particular electron velocity may be made by moving the tuning plunger 37. One advantage of this is that the frequency may be changed rapidly and conveniently, making the system particularly suitable for use as a signal generator, or as a local oscillator in a microwave superheterodyne radio receiver, for example.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An oscillator for generating high frequency electromagnetic wave energy, comprising a wave propagating structure adapted to conduct travelling electromagnetic waves at a velocity which is slow compared to the velocity of light, means for producing and directing a stream of electrons along said structure in energy exchanging relationship with waves travelling in one direction therewith, wave reflector means at the end of said structure for reversing the direction of travel of waves arriving at said end, and means coupled to said structure for conveying electromagnetic wave energy therefrom.

2. A high frequency device comprising a wave propagating structure adapted to conduct electromagnetic waves at a velocity which is low compared to the velocity of light and in a longitudinal electric mode, and reflectors at the ends of said structure, each of said reflectors comprising transition means for converting the longitudinal electric mode to a radial electric mode, said transition means including an inner conductor connected to one end of said structure and an outer conductor surrounding and radially

spaced from said inner conductor, and means for short circuiting said outer conductor to said inner conductor at a point remote from the end of said wave propagating structure.

3. A high frequency device including a wave propagating structure of a type adapted to conduct electromagnetic waves in a mode wherein the electric field vectors extend longitudinally in the direction of propagation, transition means for converting the longitudinal electric mode to a circumferentially uniform radial electric mode, said transition means including an inner conductor connected to the end of said structure and an outer conductor surrounding and radially spaced from said inner conductor, and a short circuiting plug between said inner and outer conductors.

4. A high frequency device comprising a conductive helix adapted to conduct electromagnetic waves at a velocity which is low compared to the velocity of light and in a longitudinal electric mode, and reflectors at the ends of said helix, each of said reflectors comprising a tubular conductor having a helical slot which increases continuously in pitch from that of said helix at the point of connection thereto to substantially infinite pitch at a second point on said conductor, a conductive sleeve surrounding and radially spaced from said tubular conductor, and means for short circuiting said sleeve to said tubular conductor at a point remote from the end of said helix.

5. A high frequency oscillator, including a conductive helix, an electron gun at one end of said helix and a collector electrode at the other end of said helix; terminating devices connected to the ends of said helix, said terminating devices each comprising means for converting waves travelling in a longitudinal electric mode on said helix to waves of a substantially circumferentially uniform radial electric mode, said means including a tubular conductor connected to the end of said helix, a conductive sleeve surrounding and spaced radially from said tubular conductor, and a short circuiting plug between

said tubular conductor and said sleeve at a point spaced from the end of said helix, where the electric field is radial between said tubular conductor and said sleeve; a coupling loop adjacent the short circuiting plug of one of said terminating devices, and a transmission line connected to said coupling loop and adapted to be connected to a utilization device.

6. A high frequency oscillator, including a conductive helix, an electron gun at one end of said helix and a collector electrode at the other end of said helix; terminating devices connected to the ends of said helix, said terminating devices each comprising a tubular conductor provided with a helical slot which has a pitch increasing from substantially that of the helix at its point of connection thereto to a substantially infinite value toward the other end of said tubular conductor, a conductive sleeve surrounding and spaced radially from said tubular conductor, and a short circuiting plug between said tubular conductor and said sleeve at a point further from said helix than the place where the pitch of said slot becomes substantially infinite; a coupling loop adjacent the short circuiting plug of one of said terminating devices, and a transmission line connected to said coupling loop and adapted to be connected to a utilization device.
